UNITED STATES PATENT OFFICE

EDWIN J. SCHNEIDER, OF JAMAICA, AND MERRITT B. BRADT, OF BROOKLYN, NEW YORK, ASSIGNEES, BY MESNE ASSIGNMENTS, TO GENERAL CABLE CORPORATION, OF NEW YORK, N. Y., A CORPORATION OF NEW JERSEY

ELECTRIC CONDUCTOR

Application filed February 15, 1928. Serial No. 88,828.

- This invention relates to electric conductors or cables such as are commonly used in the wiring of buildings for the supply of current thereto for lighting or other purposes.
- 5 It is an object of the invention to provide improved insulated conductors and cables. Other objects and advantages of the invention will appear hereinafter.
- The invention is fully disclosed in the following specification, of which the accompanying drawing forms a part, in which the separate parts of our improvement are designated by suitable reference characters in each of the views, and in which:—
- 10 Fig. 1 is a detail view of an electric conductor employing two metal conductors contained within a single casing illustrating the several insulation and protective casings or jackets employed;
- 15 Fig. 2 is a section on the line 2—2 of Fig. 1; Fig. 3 is a sectional, detail view of one form of laminated strip or strips which we may employ in forming one or more of the casings or jackets shown in Figs. 1 and 2; and
- 20 Fig. 4 is a view similar to Fig. 3 but showing another form of strip which we may employ.
- It will be understood that our invention relates to electric conductors and more particularly to the insulating and protective coverings employed in connection with metallic conductors. While we have shown for illustrative purposes a double wire structure such as commonly employed in house wiring, the 35 single strand conductor may be employed.
- In Figs. 1 and 2 of the drawing, 5 represents the metal conductor which may be of any desired form, size and construction, and mounted upon and secured to the conductor 40 5 are insulation casings 6 preferably composed of a plastic insulating compound such as rubber or a compound having a relatively high percentage of rubber. At 7, we have shown a protective and insulating casing, 45 jacket or wrapping which, in the construction shown, is in the form of strips of paper or other fibrous material, preferably treated with a fireproof as well as waterproof compound. Said strips are wound upon the casing 6 singly or in multiple, and in spiral ar- 50 rangement, one strip 7a being adjacent the other strip 7b if wound in multiple, and with the adjacent edges of said strips preferably overlapping as clearly seen in Figs. 1 and 4 of the drawing.
- Another casing, jacket or wrapping 8 is wound upon the casing 7 and is also preferably wound in pairs of strips 8a and 8b. The strips 8a and 8b may be similar to the strips 7a and 7b, or they may be wrapped with adjacent edges abutting as clearly shown in Fig. 3. In the latter case during the operation of winding the strips 8a and 8b into the casing or jacket 7, a plurality of strands 9, which are relatively small with respect to said strips, 55 may be interwoven with the strips 8a and 8b and extend longitudinally of the conductor and in circumferentially spaced relation. The weaving of the strands 9 is accomplished by passing each strand first over one of the strips 8a—8b, then under the next adjacent of said strips and the adjacent strands are so woven that where one strand passes outwardly over one of the strips 8a—8b, the adjacent strand passes therebeneath as clearly seen 60 in Fig. 1 of the drawing.
- The casing or jacket 8 including the strands 9 which are preferably composed of fibrous material, may be treated with a fireproof as well as waterproof compound. It will be 65 noted that it is also preferred that the strips 8a and 8b are spirally wound on the casing 7 in the same direction as the winding of the strips 7a and 7b with the strips 8a—8b overlapping the intersection of the strips 7a and 7b.
- The conductors thus formed are enclosed in a fibrous outer jacket or casing 10 preferably composed of braided fabric, so as to form a 70 non-metallic sheathed cable and the whole is treated with a water proof as well as a fire proof compound, it being understood that when a single conductor is employed, the casing or jacket 10 will be braided around 75 the same. In the structure shown, filler strands 11 are preferably employed to fill the space at the opposite sides of the adjacent edges of the separate conductors in order to 80 form a comparatively solid and well-packed 85 90 95 100

unitary structure of which the fabric braid 10 constitutes a jacket or casing.

A conductor constructed in the manner described will possess all the essential qualities 5 and properties required in conductors of the class described and for the use specified, especially from the insulation standpoint. In addition, the particular multiple wrappings or jackets employed renders the conductor 10 flexible to a degree which will meet all requirements in the use of the conductor and the woven strands 9 extending longitudinally of the conductor and interwoven with the strips 8a and 8b will serve to give materially 15 greater strength and durability to the metal conductor 5 when subjected to longitudinal stress or pull, as well as to lateral stress, operating also to avoid the rupturing of the casing or jacket 8, and if such casing or jacket 20 be ruptured due to excess bending the strands 9 will operate to retain the casing or jacket in position or against displacement.

The flexibility of the conductor above referred to is brought about primarily in the 25 winding of the strips in pairs, producing a materially greater pitch between the separate windings of each strip by virtue of the composition of the companion strip intermediate the windings of the first named strip as compared 30 with other devices of this class wherein a single strip is wound upon the conductor, necessitating almost a right angle wrap of the strip with reference to the longitudinal plane of the conductor. Due to the materially 35 increased pitch of the wrap of applicants' strip, greater flexibility is provided in the resulting product and in addition it lends economy in materially reducing the production costs by virtue of the increased speed of 40 producing the product. In addition to the foregoing, and the objects set forth in the specification, one of the principal and distinctive features of our invention resides in the direct wrapping of two spirally wound 45 casing or jackets, one upon the other, providing, by virtue of the compositions or compounds employed thereon, a certain amount of adhesion between each casing or jacket, and also permitting each casing to independently 50 take up the stress or strain to which the conductor may be subjected in the bending thereof.

Each of the strips 8a-8b shown in Fig. 1 of the drawing is preferably folded, for example 55 in the manner illustrated in Fig. 3 of the drawing. It will be noted that these strips are formed from a comparatively wide strip and the edges 8c are first drawn inwardly upon the adjacent portion of the strip on the folds of 8d and the strip thus folded is again folded inwardly at the opposite sides thereof on the folds 8e, and then folded centrally as at 8f to form a comparatively narrow strip of six-ply thickness, and the edges 60 of the strip from which the narrow strip is

formed are contained within such narrow strip. This construction will form strong and durable strips or bands which will withstand considerable stress or strain before 70 breaking.

In Fig. 4 of the drawing, we have shown a modified to enlarged scale the wrapper or jacket 7 comprising the overlapping strips 7a and 7b which may be wrapped singly or in multiple as may be desired. In said figures, we have shown two strips 12, both of which are of similar cross sectional form and in the formation of the strips 12, one side edge 12a of a comparatively wide strip is folded at 12b and again at 12c and 12d and the other side edge 12e is extended beyond one side edge of the folded portion which constitutes the strip 12 proper in such manner that the extending edge or flange 12e will overlie the strip proper of the adjacent strip 12 and form a closure and covering for the abutting edges of adjacent strips in winding the strips on the casing or jacket 6 of the conductor. It will be apparent that in treating a casing or jacket formed from the strips 90 12 with fireproof and waterproof material, a relatively closed casing or jacket is formed or a casing or jacket which will present a greater protection for the metal conductor 5 than a casing or jacket formed from abutting strips.

It will be understood that we are not necessarily limited to the specific manner of winding the strips of the protective casings herein shown and described, nor to the specific material employed in or manner of constructing said strips, nor is our invention limited to the specific arrangement of the strands 9 or method of weaving the same herein set out, and various other changes in 100 and modifications of the construction herein shown and described may be made within the scope of the appended claims without departing from the spirit of our invention or sacrificing its advantages.

Having fully described our invention, what we claim as new and desire to secure by Letters Patent, is:—

1. An article of manufacture comprising in combination, a metallic electric conductor, a body of insulating material surrounding said conductor, and a protector covering consisting of strip fibrous material wound upon said body of insulating material in spiral fashion, one winding having an edge positioned in substantially abutting relation to an edge of an adjacent winding and also having a projecting portion adapted to overlie said adjacent edges to conceal and cover the same.

2. An article of manufacture comprising in combination, a metallic electric conductor having a body of insulating material surrounding said conductor, and a protector casing for the conductor comprising spirally

wound fibrous strip material, each turn of which has an edge disposed adjacent to an edge of an adjacent turn and also has a separate portion adapted to overlie said edges to 5 form an overlap joint maintaining a closure between the separate turns in the flexure of the conductor.

3. An article of manufacture comprising in combination, an electric conductor, a 10 sheath of insulating compound surrounding said conductor, and a protector casing for the insulated conductor comprising a spirally wound fibrous strip, said strip being thicker along one edge than along the other edge and 15 being wound with the edges of adjacent turns overlapping.

4. An article of manufacture comprising in combination, an electric conductor, a 20 sheath of insulating compound surrounding said conductor, and a protector casing comprising a folded paper take which is thicker along one edge than along the other edge spirally wound about the insulated conductor with adjacent edges overlapping and 25 providing substantially cylindrical outer surface.

5. An article of manufacture comprising in combination, an insulated electric conductor, and a protector casing enclosing the 30 insulated conductor comprising a non-metallic strip which is thicker over approximately one-half of its width than over the other half of its width wound helically about the insulated conductor with adjacent convolutions 35 overlapping substantially one-half the width of the strip to provide a substantially cylindrical outer surface.

In testimony that we claim the foregoing as our invention we have signed our names 40 this 18th day of January 1926.
